UNITED STATES PATENT OFFICE

OSCAR L. LAWSON, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SOLE GROOVING MACHINE

Application filed June 12, 1926. Serial No. 115,458.

This invention relates to machines for operating upon soles and is herein illustrated as embodied in a machine for forming in the shank portion of a sole a groove to receive the stiffening rib of a shank iron or shank stiffener. In the manufacture of boots and shoes, it is customary to apply to the shank portion of the sole a stiffener or shank iron to reinforce and maintain the shape of the sole at this point. A shank stiffener of the type now quite generally employed is composed of sheet metal and is formed with a longitudinal rib to increase the rigidity thereof. This rib prevents the stiffener from lying flat upon the face of the sole and is particularly objectionable in the case of a turned shoe in which the stiffener or shank iron is located on the inner side of the sole and is covered by an attached leather shank piece. In order to produce as close a fit as possible between the sole and the shank stiffener, it has been customary, after the insertion of the stiffener, to pound the sole on an iron last, but this has not produced satisfactory results and has, moreover, tended to distort the stiffener and especially to flatten out the stiffening rib which usually comprises a corrugation formed in the metal of the stiffener.

Some attempts have been made to groove the shank portion of the sole for the reception of the stiffening rib on the shank iron, but this has been difficult of accomplishment in a satisfactory manner by means of the facilities available in the art, and has not, so far as I am aware, been done to any very considerable extent. Moreover the groove formed in the sole must be carefully formed and accurately positioned and centered if the shank iron is to be properly located and fitted, and the formation of such a groove has not been practicable in quantity production.

In view of the foregoing one object of the present invention is to provide a machine whereby soles of varying sizes may be rapidly and cheaply provided with grooves to receive and fit metal stiffeners, the grooves being automatically and accurately centered on and aligned with the shank portions of the

soles and also properly positioned longitudinally of the latter.

To the accomplishment of this object, one feature of the invention consists in the provision, in a machine for grooving soles, of sole grooving means and a work holder relatively movable to form a groove in a sole and means on the work holder self adjustable to soles of different sizes in directions both widthwise and lengthwise of a sole on the work holder for positioning the sole both longitudinally and transversely relatively to the grooving means.

More particular objects of the invention, together with means whereby the latter may be carried into effect, will best be understood from the following description of a preferred embodiment thereof illustrated in the accompanying drawings. It will be understood, however, that the particular construction described and shown has been chosen for illustrative purposes merely, and that the invention, as defined by the claims hereunto appended, may be otherwise embodied without departure from the spirit and scope thereof.

In said drawings:

Fig. 1 is a plan view of the machine with a sole in place on the work holder.

Fig. 2 is a view, in front elevation, with the work and the side positioning devices in section substantially on the line 2—2, Fig. 1.

Fig. 3 is a view, in side elevation, looking from the left in Fig. 2, showing the positions of the parts prior to the introduction of the work.

Fig. 4 is a plan view of a sole after the grooving operation.

Fig. 5 is a sectional view taken substantially on the line 5—5, Fig. 4.

Fig. 6 is an enlarged transverse sectional view of the grooved sole, showing a shank stiffener in place thereon.

In Figs. 4 and 5 is shown a sole A, the shank portion of which is provided in one face with a longitudinal groove a to receive the longitudinal rib b (Fig. 6) on a shank stiffener or iron B. The cross sectional form of the groove a is complementary to that of the rib b, thereby permitting the stiffener B to lie flat upon the sole A with the adjacent

95

100

105

surfaces of the sole and stiffener in engagement with one another throughout. The groove *a* is accurately centered with respect to the shank of the sole *A*, is alined with the median line of the sole, and is properly positioned longitudinally thereof in accordance with the length and required position of the stiffener, so that the latter may be properly positioned on the sole merely by assembling the parts with the rib *b* in the groove *a*. One form of machine for so producing and locating the groove *a* in a rapid, accurate, and convenient manner is illustrated in Figs. 1, 2 and 3.

15 The frame of the machine comprises two uprights 15 and 16 carried by a base or table 17 which is supported at a convenient height above the floor.

16 The upright 15 is provided at its top with suitable bearings in which is journaled a horizontal shaft 18 carrying a belt pulley 19 by which said shaft may be rotated from any convenient source of power through a suitable belt, not shown. One end of the shaft 18 is extended to a point substantially over the center of the upright 16 and has secured thereto a rotary grooving cutter 20 having a relatively narrow peripheral working face whose cross section corresponds to that of the rib on the shank stiffener.

17 Guided for vertical movement in the upright 16 is a slide or plunger 21 having a head 22 carrying a guide 23 extending horizontally, or in a direction perpendicular to the plane of rotation of the cutter 20 and located immediately under the latter. The plunger 21 is connected by a rod 24 with a lever 25 suitably pivoted beneath the table 17 and in turn connected by a link 26 with a treadle 27 on the floor, whereby the plunger 21 and parts carried thereby may be raised and lowered at will. The head 22 of the plunger 21 is provided with a depending stud 28 guided in a laterally projecting lug 29 on the upright 16, said stud being provided, below said lug, with an adjustable stop nut 30 held in adjusted position by a lock nut 31, said stop nut engaging the under face of the lug 29 to limit the upward movement of the plunger 21 and the guide 23.

18 Mounted on the guide 23 for movement past the periphery of the cutter 20 in a direction perpendicular to the plane of rotation of the cutter and at right angles to the axis of the cutter, is a work holder or slide 32 having means for positioning the sole thereon, said work holder being provided with suitable handles 33 whereby the same may be manually reciprocated on the guide 23. Secured to the under side of the slide 32, adjacent to one side thereof, are two angular stop lugs 34 which cooperate with stop screws 35 to limit the movement of the work holder on its guide in both directions. The stop screws 35 are adjustably mounted in laterally project-

ing ears 36 formed at the end of the head 22, said stop screws being held in adjusted position by means of lock nuts 37.

19 The means for positioning the sole *A* on the work holder or slide 32 comprise yieldingly mounted end and side positioning members. The end positioning member comprises a slide 38 having a longitudinal rib 39 guided in a suitable groove 40 in the upper face of the slide 32 adjacent the rear end of the latter, said slide 38 being normally drawn forwardly by means of a spring 41 connecting the outer end thereof with the adjacent end of the slide 32. At its forward end the slide 38 is formed with a flaring or generally V-shaped notch or recess 42 to receive and center the heel end of the sole *A*, said notch or recess being symmetrically disposed with respect to the plane of rotation of the cutter 20.

20 The side positioning members comprise bell-cranks pivoted on studs 43 projecting upwardly from the slide 32 adjacent the rear corners of the latter, said bell-cranks having segmental arms 44 extending toward and intergeared with one another, and forwardly extending substantially parallel arms 45 symmetrically disposed with respect to the plane of rotation of the cutter. The arms 44 are connected by a spring 46 exerting a pressure 95 thereon tending normally to press the forward ends of the arms 45 yieldingly toward each other. The forward ends of the arms 45 are shaped to engage and substantially fit the opposite edges of a sole *A* substantially 100 at the junction of the shank and forepart thereof, and have pivoted to their upper surfaces the wings 47 the free edges of which overlie a sole positioned between said positioning members and are yieldingly pressed 105 against the face of said sole by leaf springs 48.

21 In operation, the plunger 21 is permitted to assume its lowermost position, which it will do under the influence of gravity, as 110 shown in Fig. 3, and the slide 32 pushed into its rearmost position (determined by engagement of the rear stop lug 34 with the corresponding stop screw 35) by means of the handles 33, as also shown in said figure. A 115 sole *A* is then pushed rearwardly between the free ends of the arms 45 and into the notch 42 in the slide 38, said arms 45 and the wings 47 yielding so far as may be necessary to permit such insertion of the sole. Engagement of the heel end of the sole with the notch 42 accurately centers the former. The rearward movement of the sole is continued 120 (the slide 38 yielding to permit this additional movement) until the forward ends of the arms 45 are brought into engagement with the edges of the sole adjacent the point of junction between the shank and forepart. This operation centers the shank with respect 125 to the cutter 20, and since the heel end of the 130

sole has also been centered by the notch 42 in the slide 38, the median line of the sole is brought substantially into the plane of rotation of said cutter. The longitudinal position of the sole is also determined by the 5 points of engagement of the side positioning members therewith. The treadle 27 is then depressed, lifting the head 22 and parts carried thereby as far as permitted by engagement of the stop nut 30 with the lug 29. This 10 brings the work A into engagement with the cutter 20 which incises the same to form the forward end of the groove a. The slide 32 is then drawn forwardly by the handles 33 as far as permitted by engagement of the 15 forward stop lug 34 with the corresponding stop screws 35, thereby completing the groove. During this operation the yielding wings 47 hold the sole flat upon the work holder. The 20 treadle 27 is then released to permit the work holder to be lowered away from the cutter, and the work removed, thereby completing the cycle of operations.

It will be seen that the work is brought into 25 engagement with the cutter by elevation of the plunger 21, and that the depth of the groove cut will be determined by the point to which said plunger is elevated. This point must be such that the distance separating the 30 upper, or work-receiving, surface of the slide 32 from the periphery of the cutter, as the former is moved past the latter, is equal to the thickness of the sole less the depth of the groove. The point in question is determined 35 by engagement of the stop nut 30 with the lug 29, and this point, and consequently the depth of the groove, may accordingly be varied by adjustment of said stop nut. It will also be seen that the length of the groove 40 and the position of the rear and forward ends thereof are determined by engagement of the stop lugs 34 with the stop screws 35 and that these may also be varied by adjustment of the 45 stop screws. The machine is therefore adaptable to operation upon soles of a wide variety of shapes and sizes, and the sole positioning devices described are such as to center accurately a sole of substantially any style or size within wide limits. The machine 50 is capable of rapid operation to produce accurate results without the exercise of any considerable skill on the part of the operator.

Having thus described my invention, I claim:

- 55 1. A machine for grooving soles comprising, in combination, grooving means, a work holder guided for movement to and past the grooving means, and sole edge engaging means on said holder self adjustable to soles of different sizes and arranged to engage a sole at the forward portion of the shank for positioning the sole longitudinally on said holder and for centering said sole transversely with reference to said grooving means.
- 60 2. A machine for grooving soles comprising,

ing, in combination, grooving means, a work holder, and means on said work holder for positioning a sole thereon, said positioning means including yielding members adapted to engage respectively the end and shank portions of a sole. 70

3. A machine for grooving soles comprising, in combination, grooving means, a work holder, and means on said work holder for positioning a sole thereon, said positioning means comprising a member yieldable longitudinally of the sole and having a notch to receive the end of a sole and yielding members arranged to engage the sole edge at the shank portion of the sole to position the sole 75 longitudinally relatively to said grooving means.

4. A machine for grooving soles comprising, in combination, grooving means, a work holder, sole positioning means on said work holder guided for movement lengthwise of the sole positioned on said work holder and having a notch to receive the heel portion of a sole, a spring for yieldingly resisting movement of said member, and means self adjustable to soles of different sizes and arranged to engage the shank portion of the sole to determine the longitudinal position of the sole relatively to the grooving means. 85

5. A machine for grooving soles comprising, in combination, grooving means, a work holder, and means on said work holder for positioning a sole thereon, said positioning means including a pair of bell-cranks having arms extending toward and intergeared with one another and arms having portions engaging the sides of the sole substantially at the junction of the shank and forepart, and a spring connecting said first named arms for yieldingly pressing said last named arms toward each other. 95

6. A machine for grooving soles comprising, in combination, grooving means, a work holder, and means on said work holder for positioning a sole thereon, said positioning means including a pair of positioning members engaging the edges of the sole, means for yieldingly pressing said members toward each other, and means carried by said members respectively for yieldingly pressing said sole upon said work holder. 100

7. A machine for grooving soles comprising, in combination, grooving means, a work holder, and means on said work holder for positioning a sole thereon, said positioning means including a pair of positioning members engaging the edges of the sole, means for yieldingly pressing said members toward each other, pivoted wings carried by said members and overlying said sole, and springs for yieldingly pressing said wings against the face of said sole. 110

8. A machine for grooving soles comprising, in combination, a rotary cutter, a work holder, a guide in which the work holder is 115

- mounted for movement in a plane perpendicular to the plane of rotation of the cutter, adjustable means for limiting the movement of the work holder relatively to the guide, means for moving said guide in a path parallel to the plane of rotation of the cutter to move the work toward and from the cutter, and an adjustable stop for limiting the movement of the guide in one direction.
10. 9. A machine for grooving soles comprising, in combination, a rotary cutter, a work holder guided for independent movements toward and from said cutter and in a direction parallel to the plane of rotation thereof, independently adjustable stops for limiting said last named movement in opposite directions, respectively, and an adjustable stop for limiting the movement of said work holder toward said cutter.
10. 10. A machine for grooving soles comprising, in combination, grooving means, a work holder, and means on said work holder for positioning a sole thereon, said positioning means including a member yielding longitudinally of the sole and having a notch to receive one end of a sole, a pair of interconnected members arranged to engage the lateral edges of the sole, and means for yieldingly pressing said last named members toward each other.
11. A machine for grooving soles comprising, in combination, grooving means and a work holder relatively movable to form a groove in a sole, and means on the work holder self adjustable to soles of different sizes in directions both widthwise and lengthwise of a sole on the work holder for positioning the sole both longitudinally and transversely relatively to the grooving means.
40. In testimony whereof I affix my signature.
- OSCAR L. LAWSON.
